(57) **CLAIM**

The ornamental design for a showerhead handle, as shown and described.

DESCRIPTION

FIG. 1 is a perspective view of a showerhead handle of a hand-held shower, with a switch movable in a recess showing my new design;

FIG. 2 is a front elevational view of the showerhead handle of a hand-held shower showing my new design; and,

FIG. 3 is a right side elevational view of the showerhead handle of a hand-held showerhead with the front, with a left side elevational view being a mirror image thereof.

The broken line showing is included for the purpose of illustrating and forms no part of the claimed design.
